FIG. 2.

FIG. 3.

FIG. 4.

EDWARD HAUSER
INVENTOR
BY
Victor J. Evans

WITNESS:

Septon, Fuchs

ATTORNEY

UNITED STATES PATENT OFFICE.

EDWARD HAUSER, OF NEW YORK, N. Y.

LADY'S GIRDLE.

Application filed November 2, 1927. Serial No. 230,605.

This invention relates to improvements in ladies' girdles.

The primary object of the invention is to provide a girdle for smoothly fitting about 5 the waist of a wearer to hold the abdomen flat and firm and at the same time confine that bulge of flesh at the hips, besides serving as a garter supporter for holding the hose of a wearer snugly upon the legs.

10 Another object is to provide a combined girdle and hose supporter in which the strain upon the garters due to certain natural positions of a wearer is placed upon the back and hips of the wearer which tends to press inwardly upon the flesh about the hips.

15 A further object resides in a combined girdle and hose supporter for ladies' wear, in which the garter straps engage the tops of the hose of a wearer at the outer and inner 20 sides thereof leaving the front of the hose free of any connection, the garter straps connecting with the hose on the inner sides of the wearer's legs being suspended from the rear of the girdle and brought diagonally 25 across the hips and front of the thighs.

20 A still further object is the provision of a combination garment of the kind above mentioned which is simple in construction, comfortable when worn and which is no more 30 costly of manufacture than similar garments now on the market.

35 With these and other objects in view, the invention resides in certain novel construction and combination and arrangement of parts, the essential features of which are hereinafter fully described, are particularly pointed out in the appended claims, and are illustrated in the accompanying drawing, in which:—

40 Figure 1 is a perspective view of my improved girdle in position upon a wearer looking at the front thereof.

Figure 2 is a similar view but looking toward the rear thereof.

45 Figure 3 is an enlarged perspective view of the girdle per se.

Figure 4 is a horizontal sectional view therethrough.

50 Referring more particularly to the drawings, the reference numeral 10 designates my improved girdle in its entirety, which includes a front piece 11 and a back piece 12, both of which are of a non-elastic fabric such as satin, brocade or the like, while interposed between and stitched to the front and

back pieces are elastic webs 13—13. These webs are disposed at the sides of the garment to confine the bulge of flesh at that part of the human body when the girdle is in position thereon. The front and back piece together 60 with the elastic webs co-act to provide a complete waist encircling band which is wider at the front than at the back to comfortably fit across the abdomen of a wearer and to hold the same flat and firm.

65 The back-piece 12 is cut to provide co-extensive garter straps 14, 14 on opposite sides of the girdle which are relatively wide at their joinder with the webs but which gradually decrease in width at their outer ends. 70 The stitching of the back piece with the webs and the shape of the garter straps 14 is such that the straps will lie flat against the webs and across the front of the thigh of a wearer when the girdle is worn. The ends of the 75 straps 14 have adjustable lengths of garter elastic 15 attached thereto and which suspend garter clasps 16 of the usual well-known construction.

80 Suspended from the lower edge of the girdle at the front are outer side garter straps or tabs 17, to which adjustable lengths of garter elastic 18 are attached and which have garter clasps 19 at the ends thereof.

85 In use, the girdle encircles the waist of the wearer and the outer side garters attach to the wearer's hose at the outer sides thereof. The garter straps 14 are then brought forward over the hips of the wearer to place a slight pressure thereon to confine the flesh at 90 that part of the body, after which the clasps 16 are engaged with the inside of the wearer's hose. By attaching the garter straps to the outer and inner sides of the hose, the same permits bending of the knee of the wearer 95 without fear of damaging the hose, while any natural body strains upon the hose are taken up at the back of the girdle. The garters also prevent slipping of the girdle upon the wearer thus assuring complete comfort at 100 all times.

105 While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. A garment of the class described comprising a waist encircling band having elastic webs at the sides thereof, a pair of garter straps attached at the back of said band having hose engaging clasps at the free ends thereof, said garter straps being wider at their joinder with said band than at the outer end thereof and overlying said elastic webs when said garter clasps are engaged with the hose of a wearer.
2. A garment of the class described comprising a waist encircling band, garter straps suspended at the front sides of said band, and garter straps suspended from the back of said

band and being wider at their joinder at the back of said band than at their outer ends and overlying the sides of said band and crossing said first mentioned garter straps.

3. A garment of the class described comprising a waist encircling band embodying a front piece of non-elastic material, a back piece of the same material, elastic webs stitched to said front and back pieces, and garter straps integral with said back piece and extending forwardly and downwardly to overlie said elastic webs.

In testimony whereof I have affixed my signature.

EDWARD HAUSER.
